CLAIM

The ornamental design of a square point shovel and handle therefor, as shown and described.

DESCRIPTION

FIG. 1 is a front perspective view of a square point shovel showing any new design;

FIG. 2 is a front elevational view thereof;

FIG. 3 is a back elevational view thereof;

FIG. 4 is a left side elevational view thereof;

FIG. 5 is a right-side elevational view thereof;

FIG. 6 is a top plan view thereof; and,

FIG. 7 is a bottom plan view thereof.

The broken line disclosure is for illustrative purposes only and forms no part of the claimed design.
